UNITED STATES PATENT OFFICE.

DAVID C. BROGDEN, OF PARAGOULD, ARKANSAS.

WIRE-CLAMP FOR WIRE-STRETCHING MACHINES.

1,024,825.

Specification of Letters Patent.

Patented Apr. 30. 1912.

Application filed November 9, 1909. Serial No. 527,036.

To all whom it may concern:

Be it known that I, DAVID C. BROGDEN, a citizen of the United States, residing at Paragould, in the county of Greene and 5 State of Arkansas, have invented certain new and useful Improvements in Wire-Clamps for Wire-Stretching Machines, of which the following is a specification.

My invention relates to mechanism for 10 stretching fence wires or the wire netting used in building fences, and particularly relates to a clamp to be used in conjunction with the fence-stretching mechanism shown in my pending application, Serial No. 15 500,541, filed June 7, 1909.

The invention has for its object the provision of a clamp particularly adapted for use as above stated and arranged to grip a wire or a plurality of strands of wire.

20 For a full understanding of the invention and the merits thereof, and to acquire a knowledge of the details of construction, reference is to be had to the following description and accompanying drawing, in 25 which:

Figure 1 is a perspective view of my wire clamp applied; Fig. 2 is a fragmentary longitudinal section thereof; Fig. 3 is a fragmentary detail perspective of the middle 30 clamping lever and clips detached or disassembled.

Corresponding and like parts are referred to in the following description and indicated in all the views of the drawing by the 35 same reference characters.

Referring to these figures, 2 designates opposed clamping bars which are preferably of wood, as I have found in practice that this gives the best frictional engagement with the wires, wood being soft enough 40 to allow the wires to be somewhat impressed into its surface as the clamp is tightened. The two clamping bars are held together, preferably at their two ends and at the middle, by clamps mounted on clips which 45 enclose the two bars. These clips consist, preferably, of the two opposed links 3 and the transverse bar 4, the ends of the links 3 being reduced, screw-threaded and passed 50 through holes in the ends of the cross bars 4. Nuts 5 are attached to the screw-threaded ends. The other ends of the links 3 are provided with the transverse bolt 6 upon which is rotatably mounted a clamping eccentric or 55 cam 7 having a handle 8. The face of this eccentric is as wide as the width of the

clamping bars 2 and is formed with the opposed beveled face 7a. It will be seen that when the eccentric is turned in one position, the clamping bars may be opened out, and 60 that when turned in the other position, that is, with the handle parallel to the clamping bars, the bars will be drawn toward each other. By adjusting the nuts 5, the distance between the face of the eccentric and the 65 cross bar 4 may be increased so that the clamping bars 2 may accommodate larger wires between them. The oppositely beveled face of the eccentric head provides a narrow edge for the head which bites into 70 the wood of the clamping bars, when the eccentric head is turned into operative position, thus holding the eccentric head from accidental slipping. In addition thereto each flat beveled face 7a will act to prevent 75 the accidental binding of the clamp head when turned to a partly open position. If the face of the eccentric head was rounded it would be liable to exert a wedging action. Unless turned completely over it will prevent the free outward movement of the 80 clamping bar. The beveled face, however, permits considerable movement of the clamping bar but does not allow the eccentric head to wedge in place unless positively 85 operated to that end.

For the middle clamp, I prefer to use a slightly different construction comprising the opposed links 3a carrying the cross bar 4 at one end, and having the nuts 5, as before 90 described. These links 3a, however, at their other ends are slotted, as at 9, to engage with projecting studs 10 on the ends of the eccentric head 7a. It will be seen that the operation of this clamp, as far as drawing 95 the two clamping bars 2 toward each other is concerned, is exactly similar to the action of the clamping sockets previously described, but that the device has this advantage, that the eccentric head may be easily 100 detached from the side bars or clips 3a to permit the ready detachment or attachment of the clip thereof to the clamping bars. This is particularly important for the clip located at the middle of the clamping bars. 105 The end clips and clamps can be readily detached by merely shifting them off the ends of the clamping bars, but this might be considerable trouble with the middle clamping bar. It will be understood of course, that I 110 may make all three of the clips in the form shown in Fig. 1, if desired.

The operation of my invention is as follows: The wire net or the several strands of wire which are to be stretched are placed between the clamping bars, clips are then placed upon the bars, and the clamps closed down, forcing the bars together and rigidly engaging the bars with the wire. After the bars have been tightly engaged with the wire, the clamping bars are connected, as by 10 the hook A to any suitable tightening mechanism, such as shown in my pending application before referred to, which will draw the bars and stretch the wire tightly.

While I designed my invention particularly for use in tightening wire fences, I do not wish to be limited to this, as it is obvious that the tightening bars might be applied wherever it was desired to secure a firm grip upon a wire or series of wires.

20 My invention is simple, easily applied or removed, and I have found it thoroughly effective in practice, as by its use all the wires of the fence, or all the strands of wire netting, are evenly pulled and without danger 25 of tearing out the meshes of the wire network.

Having thus described the invention, what I claim is:—

A wire stretcher comprising parallel, op-

positely disposed bars of relatively soft material, said bars being freely movable with relation to each other and adapted to clamp a section of wire fence between them, clamping devices freely movable longitudinally upon the bars and including oppositely disposed side clips, each clip being screw threaded at one end and having an angular notch at the other, a transverse bar having perforations through which the screw threaded ends of the clip pass, a nut on the 30 screw threaded end of each clip for adjusting it relative to the transverse bar, and a cam block disposed between each pair of clips and having oppositely disposed trunnions at its ends detachably engaging in said 35 notches in the side clips, said cam block having at one side flat faces which converge toward each other at equal angles, said block also having at its side and disposed approximately at right angles a laterally extending 40 handle.

In testimony whereof I affix my signature in presence of two witnesses.

DAVID C. BROGDEN. [L. s.]
